UNITED STATES PATENT OFFICE.

WILLIAM ZUBOW, OF CHICAGO, ILLINOIS.

REFRIGERATOR LATCH.

Application filed March 22, 1927. Serial No. 177,291.

This invention relates to door fasteners or latches and more specifically to those adapted for use for refrigerator or like doors.

The object of the invention is to provide 5 a novel construction of latch which will be released when the handle of the latch is pulled to open the door, that is, moved to an unlocked or retracted position, and which when the door is moved to a closed position 10 will automatically release the latch or bolt to permit the latter to move to a locking position thereby to retain the door closed.

A further object of the invention is to 15 provide a door fastener or latch of the class described in which the keeper cooperates with a releasing device for a spring-pressed bolt or latch which is retracted by the handle and in which the releasing device cooperates with the latch to limit the projection 20 of the latter and also holds the latch positively in a retracted position.

Other and further objects of the invention are to simplify the construction of the fastener or lock by reducing the number of 25 parts and simplify the construction thereof as well as provide parts which can be easily and conveniently cast and readily assembled, thereby providing for economical construction and efficient quantity production.

30 Other objects will be apparent as the description proceeds.

In the accompanying drawings:

Fig. 1 is a front elevation of my novel latch or fastener as applied to a door particularly of the refrigerator type;

Fig. 2 is an enlarged sectional plan view;

Fig. 3 is an enlarged front elevation of the device;

Fig. 4 is a side elevation of the structure 40 as shown on Fig. 2;

Fig. 5 is a rear elevation with the back plate of the latch removed and showing the parts in position when the bolt is projected;

Fig. 6 is a view similar to Fig. 5 showing 45 the bolt retracted;

Fig. 7 is a sectional view taken on the section line 7—7 of Fig. 5; and

Figs. 8 and 9 are detailed perspective views 50 of the bolt and releasing device or trip forming part of the structure.

Referring to the drawings in detail, 10 designates a door, shown of the refrigerator type, cooperating with wall 11 as indicated at 12 and overlapping the wall 11 as indicated at 13 to provide a stop for the door when closed. The latch comprises a casing

14 preferably of rectangular outline having at the top and bottom apertured attaching flanges 15 adapted to receive screws or other fasteners 16 for mounting the same on the 60 door. The casing is a shallow box-like affair open at the back which is closed over by a detachable back plate 17 having apertures alining with the apertures 16 and secured at the center in an internally threaded 65 pivot stud 18 by means of a screw 19. At one side, the casing has an upper slot 20 for the bolt 21, which latter is slidable in the casing horizontally at the top and is adapted to be projected by a suitable 70 expandible or resilient member in the form of a coil spring 22 which engages a stud 23 projecting from one end of the bolt or latch and a similar stud 24 projecting inwardly from the opposite wall or side 25 of the casing. 75 The free end of the bolt is provided with a pair of ears 26 formed by slotting the bolt as indicated at 27, the ears being apertured as indicated at 28 to take a pivot 29 on which a roller 30 is mounted. Of course any other 80 suitable form of anti-friction member may be substituted for the roller. It should be noted that the ears 26 formed by a recess or bifurcation of the upper portion of the bolt are spaced from the bottom portion to provide a shoulder 31 and that the rear side of the bolt in line with the shoulder at the bottom has a beveled recess 32 forming a stop or shoulder 33 facing toward the free end of 90 the bolt. This bolt or latch 21 may be of 90 hollow formation and at the opposite side has a shoulder 34 adapted to engage a projection 35 on the inner face of the casing at the slot 20 while the bolt rides on an extension 36 in the upper corner. 95

Inside of the front wall 37 of the casing is an apertured lug 38, these parts taking a pivot 39 on which a releasing device or trip 40 is pivoted so that its reduced end 41 projects in the path of the bolt 21 to engage in the recess 32 and to contact with the shoulders 31 and 33 for the purpose of holding the bolt or latch in retracted or projected positions, respectively, that is, to limit the projection of the bolt when engaged with the shoulder 33 and to hold the bolt retracted when engaged with the shoulder 31. This releasing or tripping device is moved into normal engagement with the bolt by means of a spring 42 which is 100 mounted on a pin 43 held in an apertured lug 44 and an aperture in the bottom wall 105 110

of the casing and one end of the spring engages the inner face of the casing while the other end seats in a notch 45 in the trip 40. The trip has a right angular plate projection 46 extending through a slot 47 on the front of the casing beneath the slot 20 and in line with the bottom of the casing.

A bell crank lever 48 is pivoted on the stud 18 at its reduced end and one arm 49 is slotted to engage a lug 50 projecting from the bolt and the other arm 51 is also slotted and has its side portions or furcations 52 beveled to receive an arm 53 projecting inwardly substantially at right angles from the enlargement 54 of a handle or lever 55 pivoted as at 56 externally between spaced apertured ears 57 formed with and projecting forwardly from the front of the casing at its side remote from the edge of the door, the handle extending downwardly as shown on Fig. 4.

A keeper 58 is mounted on the wall 11 adjacent the free edge of the door and comprises a plate 59 apertured to receive screws or other fastening means 60 and mounting the keeper in a vertical position and in alignment with the casing proper as heretofore described. This keeper has a central web 61 projecting outwardly at right angles at its lower portion and the upper end thereof has a vertical extension 62 parallel with the plate 59 and forming the keeper proper with oppositely beveled inner faces 63. The web 61 is beveled as at 64 so as to incline downwardly and inwardly from the keeper proper 62 and the narrow lower portion thus formed as indicated at 65 has a plate portion 66 projecting at opposite sides to form an abutment to strike the projection 46 of the trip in a manner to be described.

In the operation of the device, when the door is closed and the bolt or latch 21 is projected by the spring 22, the trip end 41 is seated in the recess 32 against the shoulder 33 and the shoulder 41 engages the projection 35. In this way the projection of the bolt is limited and the bolt and roller thereof are disposed behind the keeper plate 62 with the projection 46 in front of the plate 63. When it is desired to open the door, the handle 55 is pulled outwardly and at the same time swinging the handle on its pivot 56 so that the arm 53 will throw the lever 48 on its pivot from the position shown on Fig. 5 to the position shown on Fig. 6, thus retracting the bolt and compressing the spring 22 whereby the bolt is withdrawn from behind the keeper 62. The roller during these movements prevents undue friction and at the same time permits the door to be firmly held when closed, a desideratum especially with refrigerator doors. In this position the spring 42 forces the trip end 41 against the shoulder 31 as it rides over the beveled portion 33, thus positively holding

the bolt retracted. When so operating the trip 40 will swing on its pivot so that the plate projection 46 will move inwardly in the slot 47 and when the door is closed, the projection 46 will strike the plate 66 to release the trip from in front of the shoulder 31 and thereby permit the bolt to be automatically projected by the spring 22 into locking position behind the keeper 62.

It will thus be seen that I have provided a very simple, substantial and economical form of latch or fastener which is especially adapted for refrigerator doors, but may be used in other relations and therefore I do not desire to be limited to such particular use. It is also to be understood that modifications in the particular form and arrangements of the parts may be resorted to so long as the same do not depart from the spirit and scope of the invention as claimed.

What I claim as new is:

1. In a latch for refrigerator doors or the like, a casing adapted to be mounted on the door, a bolt slidable in the casing and having a roller on its free end, a spring for projecting the bolt, a pivoted tripping member mounted in the casing and having a projection extending from the casing, means for moving the tripping device into engagement with the bolt to hold the bolt retracted and to limit the projection thereof, a bell crank pivoted in the casing and operatively connected with the bolt, a lever pivoted on the casing and having an arm to engage the bell crank for retracting the bolt when the lever is moved on its pivot to open the door, a keeper adapted to be mounted on the door frame and having a beveled portion to engage the bolt roller when the bolt is projected to hold the door closed, and a plate portion to engage the projection of the tripping device when the door is moved to closed position for releasing the tripping device from the bolt to permit automatic projection thereof behind the keeper whereby the door is held closed.

2. A latch comprising a casing, a bolt in the casing, means for projecting the bolt, a bell crank lever actuating member pivoted in the casing, one arm of which engages the bolt, a handle for actuating the bolt connected to the other arm of the bell crank lever, said bolt provided with spaced notches, a tripper adapted to engage in either of said notches, means for urging the tripper toward the bolt to engage the same in the notches, said tripper provided with a member extending out from the casing, and a keeper in which said bolt is adapted to engage and against which said tripper is adapted to contact to move the same to release the bolt.

3. A latch comprising a casing, a bolt in the casing, means for projecting the bolt, a bell crank actuating member, said bolt provided with a pin, one arm of the actuating

lever engaging the pin, a handle for actuating the bolt pivotally engaging the other arm of the lever, said bolt provided with spaced notches in one edge thereof, a tripper 5 adapted to engage in either of the notches, spring means for urging the tripper toward the bolt to engage the same in the notches, said tripper provided with a member extend-

ing out from the casing below the bolt, and a keeper in which said bolt is adapted to 10 engage, said keeper provided with an outstanding member against which the said tripper is adapted to contact to move the same to release the bolt.

In testimony whereof I affix my signature.
WILLIAM ZUBOW.
